United States Patent Office

Des. 209,433
Patented Nov. 28, 1967

209,433

MOTORIZED SURFBOARD OR SIMILAR ARTICLE

Alfred S. Bloomingdale, 131 Delfern Drive, Los Angeles,
Calif. 90024, and James G. Moran, 122 N. Rose, Bur-
bank, Calif. 91505

Filed Oct. 31, 1966, Ser. No. 4,489

Term of patent 14 years

(Cl. D71—1)

FIGURE 1 is a top plan view of a motorized surfboard or similar article showing our new design;

FIGURE 2 is a left side elevational view thereof;

FIGURE 3 is a bottom view thereof;

FIGURE 4 is a rear elevational view thereof; and

FIGURE 5 is a perspective view thereof taken from an upper rear quarter.

The portion of the claim shown in broken lines indicates a flush, removable access hatch and various control elements with the characteristic features of the claim being indicated by the full line disclosure.

We claim:

The ornamental design for a motorized surfboard or similar article, substantially as shown.
